UNITED STATES PATENT OFFICE

JOHN P. FEGELY, OF ALLENTOWN, PENNSYLVANIA, ASSIGNOR OF ONE-HALF TO GRANVILLE B. PETERS, OF ALLENTOWN, PENNSYLVANIA

DISPLAY BOX

Application filed February 5, 1929. Serial No. 337,652.

The object of this invention is to provide a false-bottom which, after the goods have been partly removed from the box, may be readily raised to bring the bottom layer or 5 layers of goods up to the top edge of the box, to thus more desirably display the goods than would be the case if the articles were permitted to lie in the bottom of the partlyemptied box, as more fully hereinafter 10 set forth.

In the drawing annexed—

Fig. 1 is a perspective view of a box or carton partly emptied;

Fig. 2 is a vertical longitudinal section 15 on the line 2—2 of Fig. 1;

Fig. 3 is a view similar to Fig. 2 showing the false-bottom raised to bring the bottom layers of articles to the top of the tray or carton;

20 Fig. 4 is a transverse sectional view on the line 4—4 of Fig. 1;

Fig. 5 is a detail perspective view of the false-bottom unfolded to the position shown in Fig. 3;

25 Fig. 6 is a miniature diagram of the blank.

Referring to the drawing annexed by reference-characters, 10 designates an ordinary rectangular box and 11 the articles packed therein.

30 Underneath the articles packed in the box, I pack my false-bottom which is constructed as follows: I take a sheet of paper-board and cut a blank having a bottom-board 12 provided at each longitudinal edge with a 35 folding supporting-flange 13 and at each end with a folding supporting-flange 14, each of these end-flanges 14 being provided with a tab 15. Before the goods are placed in the box, the false-bottom is folded up and

40 placed in the bottom of the box in the manner shown in Fig. 2, i. e., with its end-flanges 14 folded up against the bottom of the part 12, its side-flanges 13 folded up against the 45 thus-folded parts 14, with the tabs 15 folded against the under faces of the members 13 and having their tapered ends extended upwardly to lie either folded down on the upper face of the member 12 or, as shown in 50 dotted lines at the right-hand end of Fig. 2,

extending up against the side wall of the box 10.

With the false-bottom thus constructed and folded and placed in the bottom of the box 10, the articles to be displayed are 55 packed into the box 10 in the usual manner. After one or more layers of the articles 11 have been removed from the box and it is therefore desirable to bring the lower layer or layers up to the top of the box to better

60 display them, it is simply necessary to take hold of the ends of the two tabs 15 and pull them upwardly, which action unfolds the end-members 14, raising them to an upright position, as shown in Fig. 3. This action 65 automatically unfolds the side-flanges 13 to an upright position, so that all four flanges 14 and 13 stand in an upright position against the adjacent walls of the box and thus afford a firm support for the false-bottom proper 12. The tabs 15 lie between the end-flanges 14 and the adjacent side walls of the box 10 and their pulling, tapered ends will either lie down on the top face of the false-bottom 12 or be allowed to stand

70 up and lie against the inner faces of the end walls of the box 10, as shown in dotted lines at the right-hand end of Fig. 3. 75

In accordance with the provisions of the 80 patent statutes, I have herein described the principle of operation of my invention, together with the apparatus which I now consider to represent the best embodiments thereof, but I desire to have it understood that the apparatus disclosed is only illustrative and that the invention can be carried out by other means. Also, while it is 85 designed to use the various features and elements in the combinations and relations described, some of these may be altered and others omitted and some of the features of each modification may be embodied in the others without interfering with the more general results outlined, and the invention 90 extends to such use. 95

What I claim as new is:

1. A false-bottom for display boxes embodying a false-bottom proper having an under-folding, supporting end-flange at each 100 end, an under-folding, supporting side-

flange at each of its longitudinal edges, and a folding tab attached to the free edge of each one of said end-flanges and adapted to extend to a point above the false-bottom proper, for the purpose set forth.

5 2. In a display box, a false-bottom constructed of a single blank cut to form a false-bottom proper adapted to fit within the display box and lie under the goods packed therein, two side-flanges foldably connected with the longitudinal edges of said false-bottom proper, two end-flanges foldably connected to the end edges of said false-bottom proper, and a tab foldably connected to the free edge of each one of said end-flanges and adapted to extend to a point above the false-bottom proper, for the purpose set forth.

10 3. In a display box, a false-bottom provided with folding flanges at its edges adapted to fold up against the under side of said false-bottom proper when the same is placed in the bottom of the display box, and means attached to an opposite pair of 15 said flanges whereby the false-bottom may be raised within the display box and all of said flanges simultaneously unfolded to an upright position to form supports for said false-bottom in its raised position.

20 30 4. A false-bottom for a display box embodying a bottom proper having at two of its opposite edges folding flanges adapted to fold up against the under side of said false-bottom proper and adapted to be unfolded outwardly against the side walls of the box when the false bottom is raised, and means accessible from the upper side of said false-bottom for unfolding said flanges to upstanding position.

40 In testimony whereof I hereunto affix my signature.

JOHN P. FEGELY.
